UNITED STATES PATENT OFFICE

PAUL F. COX AND JOSEPH L. COX, OF CHICAGO, ILLINOIS, ASSIGNEES TO THE GOSS PRINTING PRESS COMPANY, OF CHICAGO, ILLINOIS, A CORPORATION OF ILLINOIS

INKING MECHANISM FOR TRAVELING CYLINDER PRESSES

Application filed November 19, 1928. Serial No. 320,321.

Our invention relates to web printing presses of the type shown in Cox Patents No. 988,548, of April 4, 1911; No. 1,457,501, of June 5, 1923; and No. 1,475,566, of November 27, 1923, in which the web is printed by means of traveling impression cylinders from printing surfaces resting upon stationary beds, the impression cylinders being "on impression" during their printing stroke, and "off impression" during their return stroke, so as not to contact the printing surfaces, during which return stroke the web of paper is fed forward between the beds and cylinders.

15 The present invention relates to the inking mechanism and specifically to the means for intermittently partially rotating the ink fountain rolls from which ink is supplied to the distributing and form rollers.

20 While the invention is primarily designed for use in a web perfecting press, it is applicable to single acting presses; and to other types of presses in which traveling cylinders and inking means are employed.

25 We will explain the invention with reference to the accompanying drawings which illustrate so much of a web perfecting press of the type referred to as will enable the invention to be clearly understood; and summarize in the claims the novel constructions and combinations of parts for which protection is desired.

In the drawings:

Fig. 1 is a partial side elevation of a web printing press equipped with our improved inking mechanism.

Fig. 2 is a detail sectional view on the line 2—2 Fig. 1.

Fig. 3 is a detail view of a modification.

40 The press diagrammatically shown in the drawings has parallel type beds 1, 1^a arranged one over the other in a suitable main frame. Cooperating with bed 1 is a traveling impression cylinder 2, and cooperating with bed 1^a is a traveling impression cylinder 2^a. Said cylinders are mounted in crossheads 3 which are guided in suitable ways in the sides of the press frame, and are reciprocated longitudinally of the frame preferably by means 45 of pitmen 3^a connecting the crossheads 3 with

crank wheels 4; which may be rotated by any suitable means to cause the cylinders 2 and 2^a to travel back and forth over the beds.

In the type of press shown means are provided whereby the cylinders are "on impression" during one stroke and "off impression" during their return stroke. The general construction and arrangement of such presses and of all the aforesaid parts are well known and need no further detailed explanation 55 60 65 70 75 80 85 90 95 100

herein. For further explanation of the construction and operation of such a press reference may be had to the aforesaid Cox Patent No. 1,457,501. The invention in the present case relates more particularly to the means for operating the fountain rolls.

As indicated in said patent the crossheads carry form inking rollers 5, ink distributing rollers 5^a cooperating therewith and ductor rollers 5^b. The said rollers may be arranged 70 in any preferred manner, their arrangement not constituting any part of the present invention. The ductor rollers will contact with fountain rollers 6^a in ink fountain 6 (which are mounted on the arm adjacent the outer ends of the beds,) and each time the crossheads near the limit of their outward stroke the ductor rollers will take a supply of ink from the fountain rolls and supply same to the distributing rollers during the inward 75 80 85 90 95 100 return stroke of the crossheads.

It is desirable to partly rotate each fountain roll 6^a each time it is contacted by a ductor roller 5^b. For this purpose each fountain roll has been provided with a ratchet 6^b adapted to be engaged by a pawl 7^b attached to an arm 7 pivoted on the shaft of the fountain roll, or in axial alinement therewith. The arms 7 of the upper and lower fountains have usually been connected by a link 7^c and a cam has heretofore been attached to the crossheads and so arranged that when the crossheads near the outer limit of their stroke the cam imparts a quick movement to the bar 7^c and causes it to quickly shift the levers 7 and the fountain rolls. The movement imparted to the rolls by this cam is rapid and jerky because in the operation of the press the crossheads are quickly reversed; and it is one object of the present

invention to enable the ink fountain rolls to be shifted easily and gradually during each reciprocation of the crossheads, and this object is accomplished by the following means.

- 5 The lower lever 7 is connected by a link 7^a, (which may be separate or integral with the link 7^c connecting the levers 7 of both upper and lower fountains 6) to the short arm 8^s of an oscillating lever 8 which is pivoted at 8^a on one of the side frames below the crosshead; and the long arm of the lever 8 extends beside the bed and below the path of the adjacent crosshead, and during the inward stroke of the crosshead the long arm 15 of the lever will be engaged by the crosshead or a member thereon and be depressed thereby, thus oscillating the lever 8 and through the link 7^a swinging the levers 7 upwardly and causing the pawls 7^b to impart a limited amount of rotatorial movement to the fountain rolls 6^a. On the outward movement of 20 the crosshead the long arm of the lever rises and the link 7^a descends lowering the arms 7 and retracting the pawls 7^b.
- 25 The outer end of the lever 8 may be connected to a guide pin 9 passing through a guide lug 9^a attached to the frame, and an expansion spring 9^b may be arranged, as between the lugs 9^a and lever 8, to raise the lever 8 when the crosshead moves outward, the spring being compressed when the crosshead moves inward.

As stated the long arm of the lever 8 is adapted to be engaged by a member on or attached to the adjacent crosshead. Preferably we employ a roller 10 mounted on a bracket 10^a which may be adjustably attached to the crosshead 3 by a bolt and slot as indicated at 10^b, 10^c.

40 If desired the lever 8 could be provided with an inclined cam slot 8ⁿ engaged by the roller 10, whereby the lever will be positively actuated in both its up and down movement by reason of the engagement of the roller 10 with the slot, thus obviating the use of springs to lift the long arm of the lever.

The extent of movement imparted to the levers 7 for each reciprocation of the crosshead may be varied in various ways, as by adjusting the bracket 10^a on the crosshead, or by adjusting the connection 7^c of the link 7^a to or from the pivot of the lever 8; or by adjusting the pivot 8^a of the lever. Any or all such adjustments could be made in well known manners obvious to those skilled in the art, and therefore do not require detailed illustration.

With the construction described it will be seen that each time the crossheads move outward the levers 7 are lowered and pawls 7^b retracted, and the long arm of the lever 8 rises; and as the crossheads move inward the long arm of the lever 8 is depressed thereby lifting the levers 7 and causing the pawls 7^b to actuate the ratchets 6^b and turn the

fountain rolls the desired extent. Thus for each reciprocation of the crossheads a fresh supply of ink will be furnished to each set of inking rollers by the ductor rollers, thus enabling the ink supply to be maintained regularly and uniformly. Also the fountain rolls will be moved quietly and slowly without jarring or disseminating ink by sudden quick movements of the fountain rolls.

We claim:

1. In a printing press having a traveling cylinder, inking rollers moving with the cylinder, and a fountain adjacent one limit of movement of the cylinder having a roll adapted to supply ink to the said rollers; a long pivoted lever extending along and adjacent the path of movement of the cylinder and adapted to be actuated by the linear movement of the cylinder, and means actuated by said lever for imparting a gentle intermittent rotary movement to the fountain roll.

2. In a printing press having a traveling cylinder, a system of inking rollers moving with the cylinder, an ink fountain located adjacent one limit of movement of the cylinder having a roll adapted to supply ink to the movable system of rollers, and devices for rotating the fountain roll; a long pivoted lever extending along and adjacent the path of movement of the cylinder and a member traveling with the cylinder adapted to engage gently and operate the lever as the cylinder is reciprocated; and a link connecting the said lever with the fountain roll actuating devices.

3. In a printing press having a traveling cylinder, a set of inking rollers moving with the cylinder, an ink fountain located adjacent one limit of movement of the cylinder having a roll adapted to supply ink to the said inking rollers, a lever and ratchet for rotating the fountain roll, a long pivoted lever extending along and beside the path of movement of the cylinder, and having a long arm adapted to be engaged and gently depressed by a member traveling with the cylinder as the latter is reciprocated, and a link connecting the short arm of the said pivoted lever with the fountain roll actuating device.

4. In a printing press having a traveling cylinder, reciprocating crossheads for moving the cylinder, inking rollers carried by the crossheads adjacent the cylinder, an ink fountain located adjacent one limit of movement of the crossheads having a roll adapted to supply ink to the inking rollers, and a lever and ratchet for rotating the fountain roll; a pivoted lever extending along and below the path of movement of a crosshead and having a long arm adapted to be engaged by a member on the crosshead when the latter is reciprocated, and a link connecting the short arm of said pivoted lever with the fountain roll actuating device.

5. In a printing press having a traveling

- cylinder, reciprocating crossheads for moving the cylinder, inking rollers carried by the crossheads adjacent the cylinder, an ink fountain located adjacent one limit of movement of the crossheads having a roll adapted to supply ink to the movable system of rollers, and a lever and ratchet for rotating the fountain roll; a pivoted lever extending along and below the path of movement of a crosshead, a roller attached to the crosshead and engaging the long arm of the lever as the crosshead is reciprocated, and a link connecting the short arm of the said pivoted lever with the fountain roll actuating device.
- 5 6. In a printing press having a traveling cylinder, reciprocating crossheads for moving the cylinder, a system of inking rollers carried by the crossheads adjacent the cylinder, an ink fountain located adjacent one limit of movement of the crossheads having a roll adapted to supply ink to the movable system of rollers, and a lever and ratchet for rotating the fountain roll; a pivoted lever extending along and below the path of movement 10 of a crosshead and having a long arm adapted to be depressed by a member on the crosshead as the latter is reciprocated, a link connecting the short arm of the said lever with the fountain roll actuating device, and means for raising the lever after it is depressed.
- 15 7. In a printing press having a traveling cylinder, reciprocating crossheads for moving the cylinder, a system of inking rollers carried by the crossheads adjacent the cylinder, an ink fountain located adjacent one limit of movement of the crossheads having a roll adapted to supply ink to the movable system of rollers, a lever and ratchet for rotating the fountain roll, a pivoted lever extending along and below the path of movement 20 of the crossheads and having a long arm and a short arm, a roller adjustably attached to the crosshead and engaging the long arm of the pivoted lever, as the crosshead is reciprocated, a link connecting the short arm of the said lever with the fountain roll actuating device, and spring means for raising the lever after it is depressed.
